UNITED STATES PATENT OFFICE

162,648

KITCHEN CABINET

Michael Hallward, Swampscott, Mass., assignor to Frank C. Snedaker & Co., Inc., Philadelphia,
Pa., a corporation of Pennsylvania

Application June 30, 1950, Serial No. 10,873

Term of patent 14 years

(Cl. D33—13)

To all whom it may concern:

Be it known that I, Michael Hallward, a citizen of Great Britain, residing at Swampscott, county of Essex, State of Massachusetts, have invented a new, original, and ornamental Design for Kitchen Cabinet, of which the following is a specification, reference being had to the accompanying drawing, forming a part hereof.

I claim:

The ornamental design for a kitchen cabinet, as shown.

MICHAEL HALLWARD.
